(57) **ABSTRACT**

An assembly for guiding a movable furniture part includes a guide system to be fastened to a stationary furniture part, and a support on which a movable furniture part can be pivotably mounted and which can be or is movably connected to the guide system in order to indirectly guide the movable furniture part on the stationary furniture part. The movable furniture part includes a guide device separate from the guide system, for directly guiding the movable furniture part on the stationary furniture part.

ASSEMBLY FOR GUIDING A MOBILE FURNITURE PART

BACKGROUND OF THE INVENTION

The invention relates to an assembly for guiding a movable furniture part, preferably a sliding door or folding sliding door, on a stationary furniture part, preferably a furniture carcass. Furthermore, the invention relates to a piece of furniture with such an assembly.

Assemblies of this general type are already known. A disadvantage with such solutions according to the state of the art is that the movable furniture part is only guided via the support on the at least one guide system. A movement of the support—and thus also of the movable furniture part—along the at least one guide system can be hindered or blocked by the movable furniture part because of the inadequate guiding of the movable furniture part. It is also possible that the movable and/or the stationary furniture part is or are damaged by such a movement.

SUMMARY OF THE INVENTION

The object of the present invention is to avoid the described disadvantages according to the state of the art and to specify an assembly, which is improved compared with the state of the art, for guiding a movable furniture part, preferably a sliding door or folding sliding door, on a stationary furniture part, preferably a furniture carcass, and a piece of furniture with at least one such assembly.

According to the invention, the movable furniture part has a guide device, which is separate from the at least one guide system, for directly guiding the movable furniture part on the stationary furniture part.

The movable furniture part is thus guided on the stationary furniture part not only indirectly via the support, but also directly via the separate guide device. During a movement of the support—and thus also of the movable furniture part—along the at least one guide system, the movable furniture part is thereby guided such that a frictionless course of movement is ensured.

The assembly comprises at least one adjusting device, by which at least one part of the guide device is adjustable relative to the stationary furniture part, preferably in a direction normal to a longitudinal extent of the at least one guide system.

Such an adjusting device makes an, above all also later, adjustment of the guide device to given or changing framework conditions possible. In particular, the guide device can be adjusted by the adjusting device such that the movable furniture part is guided parallel to the at least one guide system during a movement of the support—and thus also of the movable furniture part—along the at least one guide system.

Furthermore, a piece of furniture according to the invention with at least one stationary furniture part, at least one movable furniture part and at least one assembly for guiding the movable furniture part on the stationary furniture part is provided, preferably wherein the piece of furniture comprises a shaft-like cavity, in which the at least one movable furniture part can be arranged.

The guide device can comprise at least one groove and at least one guide element engaging in areas in the at least one groove. This represents an uncomplicated and cost-effective yet at the same time stable possibility for implementing a guide device.

In an embodiment of the invention, the at least one groove is arranged on the movable furniture part, preferably wherein the at least one groove extends over the entire length of an edge of the movable furniture part and that the at least one guide element is arranged on the stationary furniture part.

However, the at least one groove can also be arranged on the stationary furniture part and that the least one guide element is arranged on the movable furniture part, preferably wherein the at least one guide element extends over the entire length of an edge of the movable furniture part.

Depending on the specific application case, at least one of the two variants ensures an optimal guiding of the movable furniture part on the stationary furniture part.

If the at least one groove or the at least one guide element extends over the entire length of an edge of the movable furniture part, this contributes to an even more stable and more comprehensive guiding of the movable furniture part on the stationary furniture part.

According to a further embodiment of the invention, the movable furniture part is formed by a sliding door or folding sliding door, preferably wherein the sliding door or folding sliding door comprises only one door leaf.

Furthermore, the adjusting device can have an actuating element, by which the adjusting device is actuatable, preferably wherein the actuating element is implemented in the form of a screw. This represents a simple possibility for actuating the adjusting device.

Preferably, the assembly has a compensation device.

Particularly preferably, the compensation device comprises a pivot lever mechanism and/or a cable pull device.

Such a compensation device prevents a jamming of the support on the at least one guide system, if an overload occurs on the movable furniture part.

If the assembly comprises at least two guide systems, preferably vertically spaced apart from one another, then a more stable guiding of the support on the guide systems is guaranteed.

In relation to a piece of furniture according to the invention, the movable furniture part comprises a frame, preferably consisting of an aluminum profile, and/or a cover, preferably made of glass.

Such a formation of the movable furniture part makes a stable construction of the movable furniture part possible. In the event that the movable furniture part consists of an aluminum frame and a glass cover, then this is additionally visually appealing for users.

Particularly preferably, the profile has the groove and/or the guide element. This is a cost-effective, uncomplicated and visually appealing possibility for implementing a part of the guide device.

BRIEF DESCRIPTION OF THE DRAWINGS

Further details and advantages of the invention are explained in more detail below by means of the description of the invention with reference to the drawings, in which:

FIG. 1a shows a piece of furniture with an assembly according to the invention in a perspective view,

FIG. 1b shows a piece of furniture with an assembly according to the invention in a perspective view in an opened state,

FIG. 2a is a perspective view of a part of a piece of furniture according to the invention,

FIG. 2b is a perspective view of a part of a piece of furniture according to the invention without a side wall,

FIG. 3a is a section of a perspective view of a part of a piece of furniture according to the invention in a first position,

FIG. 3b shows detail A of FIG. 3a,

FIG. 4a is a section of a perspective view of a part of a piece of furniture according to the invention in a second position,

FIG. 4b shows detail A of FIG. 4a,

FIG. 5a is a section of a front view of a part of a piece of furniture according to the invention,

FIG. 5b shows detail A of FIG. 5a,

FIG. 6a shows a section of a first embodiment of a movable furniture part according to the invention,

FIG. 6b shows a cross section of a frame of a first embodiment of a movable furniture part according to the invention,

FIG. 7a is a section of a second embodiment of a movable furniture part according to the invention,

FIG. 7b shows a cross section of a frame of a second embodiment of a movable furniture part according to the invention,

FIG. 8a shows a section of a third embodiment of a movable furniture part according to the invention,

FIG. 8b shows a cross section of a frame of a third embodiment of a movable furniture part according to the invention,

FIG. 9a shows a section of a fourth embodiment of a movable furniture part according to the invention,

FIG. 9b shows a cross section of a frame of a fourth embodiment of a movable furniture part according to the invention,

FIG. 10 is an exploded representation of an adjusting device according to the invention,

FIG. 11a shows an adjusting device according to the invention in a first position,

FIG. 11b shows an adjusting device according to the invention in a second position, and

FIG. 11c shows an adjusting device according to the invention in a third position.

DETAILED DESCRIPTION OF THE INVENTION

A piece of furniture 100 with an assembly according to the invention in a perspective view can be seen in FIG. 1. The piece of furniture 100 comprises a stationary furniture part 3 and a movable furniture part 2 in the form of a folding sliding door with one door leaf. In the present embodiment, the door leaf is formed of a frame 2b, not visible, consisting of aluminum profiles as well as a cover 2c made of glass.

Of course, various materials can be used for frame and cover, for example wood, plastic or different metals. It can also be provided that frame and cover consist of the same material or even that frame and cover are formed in one part with each other.

The stationary furniture part 3 further has a cavity 101, which is delimited by side walls 101a. The movable furniture part 2 can be inserted into the cavity 101 at least in areas.

In the present example, a piece of furniture 100 according to the invention has further furniture sections 103 with a folding sliding door 103a and a cavity 103b. These furniture sections 103 can be either ordinary furniture sections or furniture sections with assemblies according to the invention.

In FIG. 1b it can be seen that the movable furniture part 2 has been opened and transferred into the cavity 101. The

folding sliding door 103a of the further furniture section 103 is also opened and transferred into the cavity 103b.

FIG. 2a shows a perspective view of a part of a piece of furniture 100 according to the invention. It can be seen that the side walls 101a delimiting the cavity 101 are connected to one another via connecting elements 102. A guide device 6 is hinted at.

FIG. 2b again shows a perspective view of a part of a piece of furniture 100 according to the invention, but without a side wall 101a. Two guide systems 4, 5 for guiding the support 8 on the stationary furniture part 3 can be seen. A movable furniture part 2 is mounted pivotable on the support 8 via hinges 8a.

Further, a compensation device 9, consisting of a pivot lever mechanism 9a and a cable pull device 9b, can be seen. The pivot lever mechanism 9a comprises two pivot levers, wherein the longer of the two pivot levers is arranged on the one hand pivotable on the stationary furniture part and on the other hand pivotable and displaceable substantially centrally on the support. The shorter of the two pivot levers is mounted pivotable in an upper area of the support and substantially centrally on the longer pivot lever.

The cable pull device 9b comprises a cable, which is arranged with its ends in each case on the support. The cable is connected to the stationary furniture part via guide pulleys.

FIG. 3a shows a section of a perspective view of a part of a piece of furniture 100 according to the invention in a first position. It can be seen that the movable furniture part 2 is not yet arranged in the cavity 101. Detail A of FIG. 3a is represented in FIG. 3b.

It is evident that the frame 2b has the groove 6a of the guide device 6. In this embodiment, the groove 6a extends along an entire edge 2a of the frame 2b. In particular, the groove 6a is formed by the frame 2b.

However, it can also be provided that the groove 6a extends only in areas along the edge 2a. Moreover, the groove 6a can also be formed for example by a profile separate from the frame 2b.

Further, a connecting element 102, which connects the side walls 101a, is evident. In the present embodiment, the adjusting device 7 is arranged on the connecting element 102. A guide element 6b arranged on the adjusting device 7 can be adjusted via the setting device 7. In particular, the adjustment of the guide element 6b is effected along a normal to the side walls 101a. The guide element 6b is not yet in engagement with the groove 6a.

It can also be provided that the movable furniture part 2 or the frame 2b can be adjusted by the adjusting device 7 via the guide element 6b and the groove 6a. Further, it is conceivable that the adjusting device 7 is arranged not on the connecting element 102 but rather on the stationary furniture part 3 for example via a separate fastening device.

FIG. 4a shows a section of a perspective view of a part of a piece of furniture 100 according to the invention in a first position. It can be seen that the movable furniture part 2 is arranged in areas in the cavity 101. Detail A of FIG. 4a is represented in FIG. 4b. It can be seen that the guide element 6b is now in engagement with the groove 6a, whereby the movable furniture part 2 is guided directly on the stationary furniture part 3.

For better understanding, FIG. 5a shows a section of a front view of a part of a piece of furniture 100 according to the invention. FIG. 5b again shows detail A from FIG. 5a.

It can be seen that the guide element 6b is in engagement with the groove 6a and thus the movable furniture part 2 is guided directly on the stationary furniture part 2. It also

follows from these FIGS. 5a and 5b that an adjustment of the guide element 6b via the adjusting device 7 also results in an adjustment of the position of the movable furniture part 2 in the cavity 101, thus between the side walls 101a. The adjusting device 7 can thus be inserted in order to orient the movable furniture part 2 inside the cavity 101.

FIGS. 6a to 9b show different embodiments for frames 2b according to the invention, wherein FIGS. 6a, 7a, 8a and 9a show a perspective view of the frames 2b and FIGS. 6b, 7b, 8b and 9b show an associated sectional representation in each case.

In the first embodiment according to FIGS. 6a and 6b the frame 2b has the groove 6a. Frame 2b and groove 6a are formed integral with one other. The frame 2b is formed of profiles, for example extruded profiles.

The second embodiment according to FIGS. 7a and 7b correspond substantially to the first, but a cover 2c, for example made of glass, is additionally arranged on the frame 2b.

In the third embodiment according to FIGS. 8a and 8b, the frame 2b has the guide element 6b. Frame 2b and guide element 6b can be formed integral with one other. However, the guide element 6b can also be formed by a separate part, for example made of plastic.

The fourth embodiment according to FIGS. 9a and 9b is a combination of the embodiments one and three. The frame 2b therefore has both a groove 6a and a guide element 6b.

FIG. 10 shows an exploded representation of an adjusting device according to the invention. The adjusting device 7 has a mounting device 7c, which, in the present embodiment, is arranged displaceable in a recess 102a of a connecting element 102. The guide element 6b is mounted on the mounting device 7c. It can also be provided that the groove 6a is mounted on the mounting device 7c.

The mounting device 7c has protrusions 7d, which engage in depressions 102c of the connecting element 102. Thereby, the mounting device 7c on the one hand is held in the connecting element 102 and on the other hand limits a movement of the mounting device 7c.

The adjusting device 7 further has an actuating element 7a. The actuating element 7a is connected to fixing elements 7b and a receiver 7f on the mounting device 7c. Through actuation of the actuating device 7a, the fixing elements 7b are clamped in a clamping area 7e. Since the actuating element 7a is also connected to the mounting device 7c, the mounting device is thus fixed with respect to the connecting element 102. As a result, the guide element 6b is also fixed with respect to the stationary furniture part 3.

To adjust the guide element 6b with respect to the stationary furniture part 3, the actuating element 7a is actuated, whereby the clamping via the fixing elements 7b on the clamping area 7e is released. The mounting device 7c and thus the guide element 6b can now be adjusted. After the adjustment process the mounting device 7c and thus the guide element 6b can be fixed as already described.

The drilled holes 102b in the connecting element 102 serve for fastening the connecting element 102 to the stationary furniture part 2 or to the side walls 101a.

FIGS. 11a to 11b show an adjusting device 7 according to the invention in different positions. In FIG. 11a the adjusting device is maximally adjusted in a first direction, in FIG. 11b the adjusting device is arranged in a middle position and in FIG. 11c the adjusting device is maximally adjusted in a second direction. It can be seen how the guide element 6b is

adjusted relative to the connecting element 102 and thus to the stationary furniture part 3.

The invention claimed is:

1. An assembly for guiding a movable furniture part on a stationary furniture part, comprising:
  - a first guide system to be fastened to the stationary furniture part; and
  - a support on which the movable furniture part is mounted so as to be pivotable, the support being connected movably to the first guide system for indirectly engaging the movable furniture part so as to guide the movable furniture part on the stationary furniture part, wherein the movable furniture part has a guide device, which is separate from the first guide system, for directly engaging the movable furniture part so as to guide the movable furniture part on the stationary furniture part,
  - wherein the assembly further comprises an adjusting device configured to be actuated in a direction parallel to a longitudinal extent of the first guide system, and by means of which at least one part of the guide device is adjustable relative to the stationary furniture part in a direction perpendicular to the longitudinal extent of the first guide system,
  - wherein the guide device comprises a groove and a guide element which engages with the groove, and
  - wherein the groove is arranged on the movable furniture part and the guide element is configured to be arranged on the stationary furniture part.

2. The assembly according to claim 1, wherein the adjusting device has an actuating element by which the adjusting device is actuatable.

3. The assembly according to claim 2, wherein the actuating element, by which the adjusting device is actuatable, is in the form of a screw.

4. The assembly according to claim 1, wherein the adjusting device has a mounting device on which at least one part of the guide device is mounted.

5. The assembly according to claim 4, wherein the mounting device is movably mounted in a recess of a connecting element.

6. The assembly according to claim 5, wherein the connecting element is arranged on the stationary furniture part.

7. The assembly according to claim 1, wherein the assembly has a compensation device.

8. The assembly according to claim 7, wherein the compensation device comprises a pivot lever mechanism or a cable pull device.

9. The assembly according to claim 1, further comprising a second guide system.

10. A piece of furniture comprising:

a stationary furniture part; and

the assembly according to claim 1, wherein the assembly is configured to guide the movable furniture part on the stationary furniture part.

11. The piece of furniture according to claim 10, wherein the piece of furniture comprises a shaft-like cavity, wherein the shaft-like cavity is formed by at least two side walls which are connected to one another via at least one connecting element, wherein at least one part of the guide device is arranged or formed on or in the at least one connecting element.

12. The piece of furniture according to claim 11, wherein the at least two side walls are parallel to each other.

13. The piece of furniture according to claim 10, wherein the movable furniture part is formed by a sliding door or folding sliding door.

14. The piece of furniture according to claim 13, wherein the movable furniture part is formed by the sliding door, and the sliding door comprises only one door leaf.

15. The piece of furniture according to claim 10, wherein the movable furniture part comprises a frame or a cover.

16. The piece of furniture according to claim 15, wherein the movable furniture part comprises the frame, and the frame comprises an aluminum profile, and wherein the aluminum profile has the groove or the guide element.

17. The piece of furniture according to claim 16, wherein the groove or the guide element is formed integrally with the aluminum profile.

18. The piece of furniture according to claim 15, wherein the movable furniture part comprises the frame, and the frame comprises an aluminum profile, or the movable furniture part comprises the cover, and the cover is made of glass.

19. The piece of furniture according to claim 10, wherein the piece of furniture comprises a shaft-like cavity in which the movable furniture part can be arranged.

20. The assembly according to claim 1, wherein the movable furniture part is a sliding door or folding sliding door, and the stationary furniture part is a furniture carcass, wherein the groove extends over an entire length of an edge of the movable furniture part.

21. The assembly according to claim 1, wherein the first and second guide systems are vertically spaced apart from each other.

* * * * *
